UNITED STATES PATENT OFFICE

162,156

LINT REMOVER

Marvin T. Green, Chicago, Ill.

Application June 1, 1950, Serial No. 10,294

Term of patent 14 years

(Cl. D9—2)

To all whom it may concern:

Be it known that I, Marvin T. Green, a citizen of the United States of America, residing at Chicago, in the county of Cook and State of Illinois, have invented a new, original, and ornamental Design for a Lint Remover, of which the following is a specification, reference being had to the accompanying drawing, forming part thereof.

In the drawings:

Figure 1 is a disassembled perspective view showing my new design of a lint remover, the cover being shown removed therefrom but in cooperative relationship thereto.

Figure 2 is a side elevational view of the same.

Figure 3 is a top view of my new design of lint remover, and

Figure 4 is an end view of the same.

I claim:

The ornamental design for a lint remover, substantially as shown.

MARVIN T. GREEN.
